JOSEPH EVANS, OF BUFFALO, NEW YORK.

LOCK.

1,376,141.

Specification of Letters Patent. Patented Apr. 26, 1921.

Application filed November 10, 1919. Serial No. 336,900.

To all whom it may concern:

Be it known that I, JOSEPH EVANS, a citizen of Canada, residing at Buffalo, in the county of Erie and State of New York, 5 have invented new and useful Improvements in Locks, of which the following is a specification.

This invention relates to a lock which is more particularly designed for use on sliding doors, but which can also be used for other purposes, if desired.

It is the object of this invention to provide a lock for use on sliding garage doors and for similar purposes which can be 15 readily adapted for use on either right or left-hand doors and also easily adjusted for the purpose of taking up wear and adapting the lock to the relative position of the door and the frame with which it co-operates; which is so organized that the lock cannot be opened from the outside by lifting the door, which is provided with improved means for holding the hook or latch of the door yieldingly in its operative position, which is so mounted on the door that the same cannot be tampered with from the exterior of the building, and which is provided with an improved key mechanism for operating the hook or latch.

30 In the accompanying drawings: Figure 1 is a fragmentary horizontal section of a door and frame equipped with my improved lock. Fig. 2 is a perspective view of the means for guiding the hook or latch and 35 holding the same yieldingly in its operative position. Fig. 3 is a perspective view of the hub which carries the hook and the retaining pin or key whereby this hub is connected with the stationary lock sleeve.

40 Fig. 4 is a perspective view of the lock sleeve and the face plate mounted thereon. Fig. 5 is a perspective view of the key forming part of the key mechanism. Fig. 6 is a vertical longitudinal section 45 taken on line 6—6, Fig. 1. Fig. 7 is a perspective view showing the plurality of locking disks and spacing rings forming part of the locking mechanism.

Similar characters of reference indicate 50 corresponding parts throughout the several views.

10 represents one of the upright members of the door frame and 11 one of the upright edge portions of the door which is adapted 55 to slide horizontally toward and from a ver-

tical groove 12 in the edge of the door frame when closing and opening the door.

My improved lock for connecting and disconnecting this door and door frame is constructed as follows:

13 represents a cylindrical hub or shaft which is journaled horizontally and transversely in a bearing opening 14 formed in the door and provided at its inner end with a handle 15 for turning the same. This 65 handle preferably has the form of a split ring, the opposite ends 16 of which are turned inwardly and engage with opposite ends of a transverse opening 17 in the hub which forms a pivotal connection between 70 this handle and the hub, so that this handle can be swung outward for use when it is desired to turn the hub and the same can also be swung inward so as to lie close to the side of the door when the handle is not 75 in use. At its front end the hub turns in a bearing 18 formed in the rear end of a sleeve 19 which is arranged in an opening in the front or outer part of the door. This sleeve is provided at its front end with a 80 face plate 20 which latter is rigidly secured to the door so as to be incapable of easy removal by means of bolts 21 passing through the door and engaging their heads 22 with the face plate 20, while the rear ends of 85 the bolts pass through an inner or rear face plate 23 arranged on the rear side of the door, these parts being rigidly secured together by means of screw nuts 24 applied to these bolts and bearing against the rear side of the plate 23 and upsetting or riveting the rear ends of these bolts against these screw nuts, as shown at 25 in Fig. 1.

90 Means are provided for permitting the hub to rotate to a limited extent with reference to the sleeve 19 but preventing longitudinal separation therefrom, this being 95 preferably effected by means of a pin 26 secured transversely in the side of the sleeve 19 and engaging with a segmental groove 27 arranged circumferentially on the hub, as 100 shown in Figs. 1, 3 and 4.

26 represents the shank of a latch or hook which is arranged in a recess 29 extending from the hub 13 to the vertical edge of the door, and which has its bill or beak 30 extending beyond the vertical edge of the door, while its inner or rear end 31 is provided with an external screw thread which engages with an internally-threaded opening 110

32 arranged diametrically in the hub between the ends thereof. The outer portion of this hook passes through vertical slots 33 and 34 formed respectively in the guide plate 35 which is secured to the vertical edge of the door by means of screws 36 and a catch plate 37 which is secured to the vertical edge of the frame at the bottom of the recess 12 therein by means of screws 38, 10 said frame being provided with a recess 39 in rear of the catch plate 37, so as to permit the bill 30 of the hook to engage with the inner or rear side of the catch plate 37 below the lower end of its slot 34 for connecting the door with the frame. By turning the hook on the hub the screw connection between these parts permits of adjusting the distance between the hub and the bill 30, so that the bill engages properly 20 with the catch plate and thereby permits of taking up wear and also facilitates mounting the lock. By means of the screw connection between the hook and the hub it is also possible to reverse the lock with reference to the hub and permit the lock to be 25 used either as a right-hand lock or a left-hand lock without requiring any alteration in the construction, and thus avoiding the necessity of making two forms of locks to meet this requirement. The outer face of the bill or beak of the hook is beveled, as shown at 40, so that when the door is slid into its closed position, the bill of the hook will engage the catch plate adjacent to the 30 lower end of its slot 34 and lift the hook, so as to permit its bill to pass automatically 35 behind the catch plate in a manner common to this type of lock.

The means for yieldingly holding the 40 hook in its depressed operative position which embody my improvements, are constructed as follows:

41 represents a vertically-movable follower which is guided on the rear or inner side of the guide plate 35 and is provided at its lower end with a notch or recess 42 which receives the upper edge of the shank of the hook. Projecting upwardly from the follower is a guide rod 43 which slides at 45 its upper end in a tubular guide 44 arranged on the rear side of the guide plate 35, as shown in Fig. 6. Surrounding the guide rod 43 is a spring 45 which bears at its lower end against the follower and at its upper 50 end against the guide tube 43, and which operates to yieldingly hold the hook in its lowered or operative position. The follower is guided in its downward movement and also limited in its movement in this 55 direction by means of a U-shaped guide, the horizontal legs 46 and 47 of which are secured to the rear side of the guide plate 35 while the vertical cross bar 48 thereof extends over the follower and is received by 60 a notch 49 on the inner side of the latter, as

shown in Fig. 2. As the follower rises and falls, the same is held against lateral displacement by means of the cross bar 48, and by engaging with the lower leg 47 of the U-shaped guide, the downward movement of 70 the same is limited and disengagement of the guide rod 43 from the tubular guide 44 is by this means prevented.

In order to prevent the bill or nose of the hook from being disengaged from the catch 75 plate 37 by lifting or jacking up the door, means are provided for interlocking the guide plate 35 and the catch plate 37, so as to prevent the door from being lifted. This is preferably effected by means of a retaining lug 50 arranged on the outer side of the guide plate 35 and projecting into the upper part of the slot 34 of the catch plate 37 when the door is closed, so that if an attempt is made at this time to lift the door, the lug 80 50 will engage with the upper end 51 of the slot 34, which end forms a shoulder or stop for preventing such movement and thereby prevents unauthorized opening of the door. 90

Within the front part of the sleeve 19 is arranged a key mechanism for operating the lock from the exterior of the building, which key mechanism embodies my improvements and is constructed as follows:

52 and 53 represent a plurality of locking disks and spacing rings, respectively, which are arranged in a longitudinal row within the front part of the sleeve 19 and alternate with each other. These rings and disks are 100 held against turning within the sleeve 19, this being accomplished for instance by means of a lug 54 projecting laterally from each ring and disk into a longitudinal groove 55 in the adjacent part of the sleeve 105 19, as shown in Fig. 1. Each of the disks is provided with an elongated opening 56, the openings of the several disks being in line with the openings in the spacing rings 53 and also in line with notches 57 formed 110 in the front end of the hub 13 and in line with an opening 58 formed in the face plate of the sleeve 19, as best shown in Fig. 1. The key is adapted to pass with its shank 59 through the corresponding opening 58 of the face plate, the several locking disks 52 and spacing rings 53, and engage a pair 115 of prongs 60 at its inner or rear end with the notches 57 in the front end of the hub for turning the latter together with the hook and releasing the bill 30 from the catch plate 37, this turning movement of the key being effected by means of a handle 61 arranged at the outer end thereof. The shank or body of the key is provided at its opposite longitudinal edges with notches 62 which are adapted to register with the corresponding portions of the face plate 20 and the several locking disks 52, and thereby 120 permit the key to be turned for operating 125 65 a notch 49 on the inner side of the latter, as 130

the hub and the hook connected therewith. It therefore becomes necessary to employ a key having its notches 62 properly located in order to permit of operating this lock. 5 By varying the thickness of the locking disk 52 and the spacing rings or washers 53 and employing a key having its notches 62 constructed accordingly, various permutations or combinations may be formed which will 10 permit of making each lock different from others, and thereby insure greater security against tampering.

I claim is my invention:

1. A lock comprising a catch, and two plates adapted to be secured to a door and frame respectively and provided with slots adapted to receive said hook, one of said plates being provided with a retaining lug, and the other plate being provided with a 20 shoulder adapted to be engaged by said lug.
2. A lock comprising a rocking hook, a plate provided with a slot which receives said hook, and means for yieldingly holding said hook in a depressed position comprising 25 a follower provided with a notch which receives said hook, a guide rod connected with said follower, a guide tube on said plate

which receives said rod, and a spring surrounding said rod and engaging its opposite ends with said tube and follower. 30

3. A lock comprising a rocking hook, a plate provided with a slot which receives said hook, and means for yieldingly holding said hook in a depressed position comprising 35 a follower engaging said hook, a guide rod connected with said follower, a guide tube which receives said rod, a spring interposed between said tube and follower, and a U-shaped guide mounted on said plate and extending over said follower. 40

4. A lock comprising a rocking hook, a plate provided with a slot which receives said hook, and means for yieldingly holding said hook in a depressed position comprising 45 a follower engaging said hook, a guide rod connected with said follower, a guide tube which receives said rod, a spring interposed between said tube and follower, and a U-shaped guide having its legs secured to 50 said plate, and said follower being provided with a notch which receives the cross bar of said U-shaped guide.

JOSEPH EVANS.
